UNITED STATES PATENT OFFICE.

PHILIP A. McLAUGHLIN, OF CHESTER, PENNSYLVANIA.

HAIR-BOBBING DEVICE.

Application filed July 29, 1922. Serial No. 578,874.

To all whom it may concern:

Be it known that I, PHILIP A. McLAUGHLIN, a citizen of the United States, residing at Chester, in the county of Delaware and 5 State of Pennsylvania, have invented new and useful Improvements in Hair-Bobbing Devices, of which the following is a specification.

My invention relates to hair-cutting devices and more especially to a device adaptable for use during the operation of curling women's hair or in cutting the hair of women or children in that style commonly known as bobbed.

One of the objects of my invention is to provide a device of the character described which when placed in operative position upon the head will indicate the line at which the hair is to be cut when being bobbed, also 20 to securely hold the hair so that a proper cutting line may result and to be of use in holding the hair in a desired position during the operation of curling. Another object is to provide a device of this character which 25 shall, beside having the functions above set forth, be readily adjustable to a head of any given shape or size so that the hair may be cut in lines properly proportionate thereto; and which shall be of simple construction, 30 durable, of few parts, may be easily positioned on or removed from the head and which shall have other advantages and results that may hereinafter appear.

Referring to the drawings in which like 35 numerals of reference indicate corresponding parts,

Fig. 1 is a side elevation view of my device, applied to a head.

Fig. 2 is a detail view in perspective of 40 my device showing the operative relation of the parts.

Fig. 3 is a perspective view, enlarged, of a section of a spring band member carrying a series of angularly projecting hair gripping stays.

Fig. 4 is a side elevation of a holding member or modified form of my device, applied to the head without the use of other holding and adjusting means shown in my 50 device illustrated in Fig. 2.

Referring more particularly to the drawings my device consists of a spring band member 1, formed of a preferably flat band of spring steel or other suitable resilient 55 material of oblong formation open at one end and provided at its extremity with out-

wardly turned back portions 2. Angularly extending from the inner face of this member 1, for its entire length, are a series of gripping or retaining stays 3, spaced apart 60 from each other and preferably formed of angularly bent pieces of round wire or other suitable material, which when the device is applied to the head will not cut or otherwise damage the hair tissue. Disposed in 65 spaced relation to each other on the spring member 1 are the standards or vertical guides 4 carried by the lug like steps or supports 5. Upon the standards 4 I slidably mount the members 6 and 7. The member 70 6 is bridged diametrically across the spring member 1 while the member 7 is arranged on the member 4 at substantially right angles to the member 6. The members 6 on its opposite ends is provided with bosses 75 8 each having a suitable aperture adapted to receive the vertical standard 4 and permit of a sliding adjustment of the member 6 thereon. The member 6 may be locked in any position of vertical adjustment on the 80 member 4 by means of a thumb screw 9 or other suitable fastening means. The cross member 7 is made in two sections in slidable relation to each other and adapted to be held together substantially at the point 85 where the member 7 crosses the member 6, by means of a thumb nut and screw 10 operating in corresponding slots 11 in the respective sections of the member 7. One end of the member 7 is slidably mounted on the 90 standard 4 by a boss 8 provided with an aperture to receive the standard 4 and a locking thumb screw 9 similar to those upon the cross member 6. The forward section of the member 7 is attached at its free end to an 95 annular disc or plate 12 which is carried upon laterally disposed upper end portion of a supporting bar 13. This supporting bar 13 carries a sliding collar 14 adapted to be moved along the length thereof to any 100 desired position and an extending screw or locking member 15 is adapted to lock said collar in adjusted position on the bar 13. The extending body portion or shank of the locking member 15 is provided with eye- 105 letted lugs or collars 16 to which are connected the ends of spiral retractile springs 17, the opposite ends of which are connected to the turned back end portions 2 of the spring band member 1. Below the collar 14 110 there is mounted on the bar 13 a collar 18, adapted to slide thereon and be locked in

any position of adjustment by thumb nut 19. Extending laterally from said collar 18 and integral therewith is an arm 20 on the end of which is carried an annular disc or plate 21, similar to the disc or plate 12 on the upper end of the bar 13. The bar 13 the collar discs 12 and 21 may be made of metal or any other suitable material of sufficient strength, while the cross members 6 and 7 10 may be made of spring steel or any other suitable material of sufficient resiliency and strength for the purpose intended.

It will be seen from the foregoing description of my device that the cross pieces 6 and 7 being slidably mounted upon the vertical standards 4 are capable of common adjustment to any height from the spring member 1 and that thereby the spring member 1 may be placed in any position in reference to the 20 height of a head by this adjustment. By the adjustment of the tension of the springs 17 and because the member 1 is of resilient material my device will obviously be adjustable to heads of any circumferential size. 25 Also in order to adjust the device to heads of varying depth, considered from the front to back, it will be evident that the provision of a slidably adjustable front portion of the transverse member 7 together with its 30 connection to the supporting bar 13 accomplishes this while at the same time affording a proper holding of the device upon the head by the discs 12 and 21 which are adapted to be so adjusted as to be positioned one 35 upon the forehead and the other upon the chin of a person to whom my device is applied.

It will be further seen that when the device is applied as shown in Fig. 1 and the 40 spring band 1 partially encircles the head of the wearer the gripping stays 3 will be imbedded in the hair and retain and hold sections of the hair between the respective members of the series in such a manner that 45 when the hair cutting or curling operation is taking place the hair will be firmly held thereby in the required position and the cutting can be accomplished in such alignment as the operator wishes. It is also apparent that any degree of adjustment for tightness 50 of the band around the head may be affected by the tightening of the springs 17 and that any adjustment of the device of front to back may be accomplished by the further adjusting of the transverse bar 7 upon its 55 locking nut 10.

The gripping stays 4 are formed by angularly bending preferably round wire in the formation shown in Fig. 3 and inserting 60 their ends into apertures in the spring band 1 where these ends are securely fastened by means of staggering or by any other suitable method.

It will be observed in Fig. 4 I have applied a portion of my device to the head of

a wearer without the use of other means of adjusting the same thereto than a binding strap or resilient end piece. This modified form of my device is usable at a time when the line at which the hair is to be cut is of a height which will permit its application to the head so that the tension of the spring band 22 with the tightening or resilient member 23 attached thereto will hold the band 22 securely in position. When this modified form is in the position shown in Fig. 4 it is applicable for use in the cutting of the back and sides of the hair; but when it is desired to cut the frontal part of the 70 hair in the form of a bang the spring band 22 and the resilient band 23 are somewhat loosened or spread apart and the whole is placed upon the head so that the band 23 will be positioned at the back of the head while the band 22 will be in the front of the head, thus allowing the gripping stays 4 (arranged on the inner face of the band 22 similar to that shown on the band 1 in Fig. 2), to hold the hair in front for the cutting operation. The band 22 may be of 80 material and construction similar to the band 1 in Fig. 2, while the closing resilient band 23 may be of rubber or any other suitable material having sufficient elasticity to 85 properly hold the band 22 in place. 90

It will be obvious from the foregoing that to apply my device to the head of a wearer it is only necessary to adjust the transverse bar 7 to the right length toward the front and the transverse bars 6 and 7 to 100 the right height in relation to the spring band 1 and as the result of this the disc 12 will properly press upon the forehead while the disc 21 may be then adjusted to properly press against the chin, which combined 105 adjustment results in a firm holding of the parts upon the head and a firm gripping of the head and hair by the spring band 1 and the teeth or gripping stays 3, so that 110 the hair is firmly held during the cutting operation to insure a correctly cut line.

The device is of equal facility in the operation of curling hair in that when adjusted it holds the body of the hair which is not intended to be curled securely placed 115 so that the free end of the hair extending from beneath the control of the spring band 1 may be properly manipulated by the operator to produce the desired effect.

Although I have described my device in 120 detail and shown a specific embodiment of one form thereof, I do not wish to be limited thereby, for it is obvious that modifications and changes may be made in the construction, combination, organization and arrangement of the parts thereof without departing from the scope of my invention.

Having thus described my invention what I claim as new and desire to secure by Letters Patent is

1. In a device of the character described, the combination of a resilient gripping member, oppositely diametrically disposed, transverse bridging members adjustably carried thereon, vertically adjustable supporting means carried by one of said bridging members and adapted for facial contact, adjusting spring members co-operating with said resilient gripping member and said supporting means, and a series of hair retaining stays on the inner face of said resilient gripping member adapted to hold the hair of a wearer against displacement during the operation of cutting.
- 5 2. In a device of the character described, the combination of a resilient gripping member, standards vertically mounted thereon, transverse members mounted on said standards and bridging said resilient gripping member, a supporting bar carried 20 by one end of one of said transverse members, contact discs mounted on said supporting bar, means adapted to adjustably position one of said discs along the length of said supporting bar, a member slidably 25 mounted on said supporting bar and angularly extending therefrom spring members engaging said angularly extending member and opposite ends of said resilient gripping member adapted to hold said gripping member in operative position, and a series of spaced angularly disposed gripping stays carried upon the inner face of said resilient gripping member adapted to hold the hair of a wearer against displacement during the 30 35 operation of cutting.

In testimony whereof I affix my signature.

PHILIP A. McLAUGHLIN.
